UNITED STATES PATENT OFFICE

2,611,110

ELECTRONIC DISCHARGE DEVICE OF THE CAVITY RESONATOR TYPE

Donald M. Powers, Boston, Mass., assignor to Raytheon Manufacturing Company, Newton, Mass., a corporation of Delaware

Application April 19, 1944, Serial No. 532,012

9 Claims. (Cl. 315—40)

1

This invention relates to a magnetron oscillator of the plural-anode cavity type which is adapted to generate oscillations of hyper-frequency having wave lengths of the order of a few centimeters or less. In such devices the wave length which is generated is dependent upon the geometrical size of each anode cavity, and thus for their short wave lengths the anode cavities must be made correspondingly small. The amount of power which each cavity can generate is correspondingly limited. Thus in a magnetron in which the usual number of anode cavities exists, the power which such a magnetron can deliver is comparatively low. Attempts to increase the amount of power which such a device can develop by increasing the number of the anode cavities have heretofore introduced considerable difficulties. For example, such a device tends to generate various spurious oscillations with a resulting decrease in efficiency. Likewise the effectiveness of anode cavities remote from the output coupling device decreases so that in some instances such anode cavities contribute very little, if anything, to the power supplied by the device.

An object of this invention is to devise a magnetron oscillator which is capable of generating substantially increased amounts of power of short wave lengths.

Another object is to devise such a magnetron in which the efficiency and effectiveness of the device as a whole is substantially increased.

A further object is to provide such a magnetron with a comparatively large number of anode cavities, together with a common cavity resonator into which energy is fed from a plurality of points on the anode structure.

A still further object is to devise an arrangement whereby the cavity resonator may be adjusted to provide for a substantial maximum of coupling efficiency with the oscillating portions of the magnetron, and also to provide means therein whereby tuning of the entire device may be accomplished through a significant range.

The foregoing and other objects of this invention will be best understood from the following description of exemplifications thereof, reference being had to the accompanying drawings wherein:

Fig. 1 is a vertical cross-section of one embodiment of my invention taken along line 1—1 of Fig. 2;

Fig. 2 is a transverse cross-section taken along line 2—2 of Fig. 1;

2

Fig. 3 is a view similar to Fig. 1 of another embodiment of my invention taken along line 3—3 of Fig. 4;

Fig. 4 is a cross-section taken along line 4—4 of Fig. 3; and

Fig. 5 is a diagrammatic illustration of a cavity resonator.

The magnetron illustrated in Figs. 1 and 2 comprises a tubular anode structure 1 made of a cylinder of conducting material, such as copper. A plurality of radially-disposed plates 2 likewise formed of a conducting material, such as copper, are soldered in place along the inner surface of the hollow cylinder 1. Each pair of plates, together with the intervening portion of the cylinder 1, define an oscillatory cavity. Each of these cavities is small enough to generate oscillations of the desired short wave length. Although each of these cavities is capable of generating a comparatively small amount of power, there are provided a comparatively large number of radial plates 2 and thus a comparatively large number of said cavities in order that the total power of the device may reach a comparatively high value.

The inner ends of the radial plates 2 are adapted to serve as anode faces for receiving electrons emitted from the centrally located cathode 3. This cathode is preferably of the thermionic, indirectly-heated, oxide-coated type having an interior heater 4 and an outer cathode sleeve 5 coated on its exterior surface with suitable electron-emitting oxides. Alternate plates 2 are preferably electrically connected by means of conducting straps 7, 8, 9 and 10. The straps 7 and 8 are located at one end of the anode structure, the strap 7 being electrically connected to the alternate plates 2, while the strap 8 is connected to the intervening alternate plates. At the other end of the anode structure the strap 9 is connected to those plates to which the strap 8 is connected, and the strap 10 is connected to those plates to which the strap 7 is connected. Such a strap arrangement decreases the tendency for the device to operate in various spurious modes, and reinforces the tendency of the tubes to oscillate in the primary desired mode.

The energy developed within the oscillating cavities or chambers is adapted to feed into a common cavity resonator 11. This cavity resonator is formed by the space between the cylindrical member 1 and an outer cylindrical wall member 12 likewise formed of a suitable conducting material, such as copper. The interior

of the device is hermetically sealed by upper and lower cap members 13 and 14 hermetically soldered in place at the upper and lower ends, respectively, of the cylindrical members 1 and 12. A pair of upper and lower magnetic pole pieces 15 and 16 are set into and hermetically soldered in openings in the upper and lower cap members 13 and 14, respectively, thus completing the hermetically-sealed enclosure. The magnetic pole pieces 15 and 16 may be energized with a magnetic field supplied from an external electromagnet or permanent magnet in a manner as shown and described in the copending application of William C. Brown, Serial No. 503,622, filed September 24, 1943, and now U. S. Patent No. 2,416,899. In order to support the cathode 3 within the hermetically-sealed enclosure, said cathode is mounted at the upper end of a hollow conducting tube 17 electrically connected to the cathode sleeve 5. Said hollow tube extends through an opening 18 formed in the magnet pole 16. The tube 17 is carried by the upper end of a hollow conducting rod 19. The upper end of the heater 4 is electrically connected to the cathode sleeve 5, while the lower end of said heater is connected to a conductor 20 which extends through the tube 17 and the hollow rod 19, and passes out through a glass seal 21 carried at the lower end of the hollow rod 19. A metal sealing sleeve 22 is set into and soldered in place in an enlarged opening 23 formed in the pole piece 16 and communicating with the opening 18. One end of a glass tube 24 is sealed to the lower end of the sealing sleeve 22. The other end of said glass tube is sealed to a sealing cup 25 connected to and hermetically joined with the lower end of the hollow rod 19. By the above arrangement the cup 25 serves as the external electrical connection for the cathode, and the cup 25 together with the conductor 20 serve as the external electrical connections to the heater 4.

In order that the energy developed by the oscillating chambers formed by the anode plates 2 may be fed into the cavity resonator 11, coupling slots 26 are formed through the wall of the cylindrical member 1 and connect a predetermined number of oscillating chambers disposed around the anode structure with the cavity resonator 11. In order that the impedance of the oscillating anode structure may be matched to the impedance of the cavity resonator, the slots 26 are formed as impedance transformers. For this purpose each slot 26 has a greater length looking into the oscillating anode structure, and a smaller length looking into the cavity resonator 11. This provides an impedance transforming discontinuity 27 within the slot 26. By proper dimensioning, the desired impedance matching may be secured. The energy delivered to the cavity resonator 11 may be led out to a suitable utilization device by a proper output coupling arrangement. In the present embodiment the cylindrical member 12 is provided with an elongated slot 28, the narrow dimension of said slot appearing in Fig. 2. Said slot feeds energy from the cavity resonator 11 into a choke coupler device 29. This choke coupler consists of a hollow tubular conducting member 30 hermetically soldered in place on the external wall of the cylindrical member 12. The member 30 may be provided with a central passage 31 serving as a hollow wave guide. The outer end of the member 30 may be provided with a suitable quarter-wave length choke slot 32. In order to complete the hermetic seal of the device,

5 a glass member 33 is sealed across the open end of the member 30. A hollow wave guide 34 presented to the end of the member 30, as shown in Fig. 2, will be properly coupled to the device in such a manner that said hollow wave guide 34 will be energized to feed energy from the oscillating tube to a suitable external consumption device. If further impedance matching is desired so as to eliminate reflections within the choke coupler 29, a conducting inset 35 may be inserted in the opening 31 so as to provide an impedance transforming discontinuity therein.

10 In order that the energy supplied through all of the slots 26 shall combine with maximum effectiveness in the cavity resonator 11, the location of said slots 26 as they enter the cavity resonator 11 must be matched to the pattern of waves as established in said cavity resonator. In other words, each slot 26 is preferably located at maximum 15 of the standing wave created in the cavity resonator, and should be in the proper phase relation with respect thereto so as to reinforce said wave. In order to satisfy the above requirements, the distance along the cavity resonator between 20 adjacent slots 26 should satisfy the following relationship:

$$L = \frac{n_1 \lambda g}{2} \quad (\text{Equation 1})$$

25 where n_1 is any whole number and λg is the wave length of the wave within the cavity resonator 11. If adjacent slots 26 communicate with oscillating anode chambers which are in time phase with each other, then n_1 should be an even number, while if adjacent slots 26 communicate with anode cavities which are substantially 180° out of time phase with each other, then n_1 should be an odd number.

30 If cavity resonator 11 were provided in a completely toroidal form with no ends thereto, the location of the slots 26 in accordance with the above relationships would automatically establish the locations of the maxima of the standing wave within the cavity resonator. Under such conditions it might be difficult to design a structure in which the relationships as described above are satisfied to a maximum degree, and therefore with a resultant maximum of efficiency of the device. It is therefore desirable that means be provided for securing some degree of adjustment of the wave pattern within the cavity resonator 11 for the purpose of matching said pattern to the locations of the slots 26. For this purpose the cavity resonator 11 is provided with terminal plates 36 and 37 formed of conducting material extending across and substantially completely closing the cross-sectional area of the cavity resonator. The position of the plates 36 and 37 may be adjusted by links 38 and 39 pivoted to the backs of said plates, respectively. Both links 38 and 39 are also pivoted to the lower end of an adjusting rod 40. The adjusting rod 40 is carried by the lower end of a hermetically-tight bellows 41 sealed in the walls of a tubular housing 42, the lower end of which is hermetically sealed in the wall of the cylindrical member 12. The bellows 41 also carries an adjusting screw-rod 43 which is threaded into the center of an adjusting plate 44 rotatably mounted in the upper end of the housing 42. The adjusting plate 44 preferably extends beyond the sides of the housing 42, and may be provided with a knurled edge for ready rotation and adjustment of the screw 43. By rotating the adjusting plate 44, the rod 40 is moved longitudinally, thus adjusting the posi-

tions of the plates 36 and 37. In order to guide the plates 36 and 37 in their motion, the plate 36 may be provided with a curved rod 36' fitting into a correspondingly curved sleeve 37' carried by the plate 37.

Since the device as described above is capable of generating and delivering large amounts of power, it may be desirable to provide means for cooling the device. For this purpose holes 45 may be drilled longitudinally through the walls of the cylindrical member 1. These holes feed into common passages 46 and 47 at the upper and lower ends respectively of said cylindrical member 1. Pipes 48 and 49 may be connected to the structure for supplying and carrying away the necessary cooling fluid. In this way a cooling medium, such as water or air, may be supplied to the device to keep its temperature within reasonable limits.

The cavity resonator 11 is substantially equivalent to a cavity resonator having the simple form as illustrated in Fig. 5. This cavity resonator has a length l and a transverse dimension b . The equations relating the dimensions b and l , the free space wave length λ , and the wave length λ_g within the cavity resonator are

$$\lambda_g = \frac{\lambda}{\sqrt{1 - \left(\frac{\lambda}{2b}\right)^2}} \quad (\text{Equation 2})$$

and

$$l = \frac{n\lambda_g}{2} \quad (\text{Equation 3})$$

where n is an integer. Also

$$\lambda = \frac{c}{f} \quad (\text{Equation 4})$$

where c is substantially the velocity of light and f is the frequency of the oscillations generated within the anode structure of the tube.

In order that the conditions of Equation 1 shall be satisfied, λ_g should have a particular length dependent upon the spacing between the slots 26. From Equation 3 we see that the value of λ_g may be adjusted by varying l . Such a variation is provided by the adjustment of the positions of the plates 36 and 37, as described above, between the surfaces of said plates through the cavity resonator.

Since the plates 36 and 37 are formed of conducting material, it is clear that the wave pattern set up within the cavity resonator 11 will have minima at said plates. We have already seen from the above discussion that the distance between said plates through the cavity resonator 11 is equal to an integral number of half wave lengths. Therefore, the location of the plates 36 and 37 also establishes the positions of the maxima of the wave within the cavity resonator. Thus a shifting of the plates 36 and 37 as a unit around the wave guide will shift the entire pattern of the wave therein, so that maxima of said wave may occur at the slots 26. Such a matching of the maxima with the slots 26 may be accomplished by predetermining the position of the pair of plates 36 and 37 in the initial construction of the tube. Also a certain degree of adjustment can be secured by bending the adjusting screw 43 so as to displace the plates 36 and 37 to one side or the other of the axis of the housing 42.

Since the dimension b appearing in Equation 2 is fixed by the distance between the inner surfaces of the caps 13 and 14, we see from said

equation that the value of λ_g , as called for by the adjustment of the plates 36 and 37, will in turn require a particular value of λ , and thus a particular value of f , as required by Equation 4. For maximum effectiveness, therefore, the anode structure should be designed so that it normally tends to oscillate at such a frequency. If, however, the frequency at which the anode normally tends to oscillate differs somewhat from the frequency, as required by the adjustment of the plates 36 and 37, the cavity resonator 11 will reflect a sufficient amount of reactive impedance into the oscillating anode structure to pull the frequency thereof into agreement with the frequency called for by the value of f resulting from the positioning of the plates 36 and 37. However, for maximum effectiveness it is desirable that the normal frequency of the anode structure should agree with the frequency as required by that value of f in which the wave pattern within the cavity resonator 11 is matched to the positions of the slots 26.

A certain degree of tuning or variation in the frequency of the oscillator may be secured by adjustment of the positions of the plates 36 and 37. A variation in l varies λ_g , and from Equation 2 we see that with a fixed value of b , such a variation should produce a variation in λ . However, attempts to vary the positions of the plates 36 and 37 away from a condition in which the wave pattern in the cavity resonator 11 is matched with the positions of the slots 26 will decrease the effectiveness of the transfer of energy from the anode structure to the cavity resonator. Thus only a comparatively slight degree of this type of tuning can be tolerated in the tube.

If it is desired to secure a greater degree of tuning and flexibility of adjustment than that possible with the embodiment as described above, the arrangement as shown in Figs. 3 and 4 may be utilized. In these figures the same reference numerals which appear in Figs. 1 and 2 are applied where the elements are identical. In the arrangement as shown in Figs. 3 and 4 the common cavity resonator is formed as a chamber 50 formed by the space between the cylindrical member 1 and the outer cylindrical wall member 51 formed of a suitable conducting material. The cylindrical wall member 51 extends to substantially beyond the upper end of the cylinder 1, and is hermetically sealed by a cap 52 hermetically soldered in place in the top of said cylinder 51. The cap 52 has a central opening across which is sealed a flexible diaphragm 53. The diaphragm 53 has rigidly secured to its center a rod 54 which carries a tuning member 55 at its lower end. This tuning member is formed of conducting material having a lower ring-shaped surface 56 which fits into the annular space between the members 1 and 51 and defines the upper surface of the cavity resonator 50. The upper end of the cylindrical member 1 may be closed by a cap 57 soldered in place thereon. In order to adjust the position of the surface 56, the diaphragm 53 has secured to the center thereof a threaded stub 58 extending outwardly from the device. The stub 58 is received in a threaded hub 59 of an adjusting plate 60. The hub 59 is rotatably mounted in the cover member 61 bolted onto the cap 52. The adjusting plate 60 preferably extends beyond the edges of the cover member 61 and is knurled so as to provide for a ready rotation of said plate with the consequent adjustment of the position of the surface 56. An upper pole piece 62 may be placed

adjacent the upper end of the structure cooperating with the pole piece 16 to create a magnetic field within the device, as described in connection with the pole pieces 15 and 16 of Fig. 1.

Instead of coupling the oscillating chambers within the anode structure to the cavity resonator 50 by means of slots, the alternative arrangement as shown in Figs. 3 and 4 may be utilized. In this arrangement a coupling loop 63 is placed in each of certain anode chambers. One end of the coupling loop is mechanically and electrically connected to the inner wall of the cylinder 1. The other end of the coupling loop extends out through openings in the cylindrical member 1 into the cavity resonator 50 so as to form probes 64 therein. The relationship of the probes 64 to the cavity resonator 50 should be substantially as described in connection with the relationship between the slots 26 in the cavity resonator 11 of Figs. 1 and 2.

Instead of using the type of output coupling as described in connection with the previous embodiment, this second embodiment may be provided with an alternative output coupling arrangement, as shown in Fig. 4. In this arrangement a probe 65 formed as the extension of a conductor 66 extends into the cavity resonator 50. The conductor 66 extends through pipe 67 and passes out through a glass seal 68 carried by the outer end of said pipe. The pipe 67 is likewise hermetically sealed in the wall of the cylindrical member 51. An additional hollow conducting pipe connected to the pipe 67 may surround the conductor 66 so as to form a concentric transmission line through which the energy may be led to a suitable utilization device. The probe 65 should be located at a maximum point on the standing wave within the cavity resonator 50 so as to receive a maximum amount of energization.

When the device as described above is energized, oscillations will be generated in the anode structure, will pass by means of the probes 64 in the cavity resonator 50, and will be led out through the concentric transmission line, including the conductor 66. Since the tuning surface 56 must be free to move up and down in the annular space between the cylinders 1 and 51 for tuning purposes, there will necessarily be a small space between the walls of these cylinders and the side walls of the depending annular portion of the tuning member 55. However, there will be very little tendency for any of the high frequency energy to be propagated through these spaces. Due to the close spacing between these members, a relatively high capacity will exist across the above-mentioned gaps. This high capacity will present a relatively low impedance to the hyper-frequency energy, and thus will substantially short-circuit the gaps. In order to insure against the loss of any hyper-frequency energy through the gaps, the walls of the depending annular portion of the tuning member 55 may be provided with quarter-wave length choke slots extending around the entire circumference of the outer and inner gaps existing between the member 55 and the cylindrical members 51 and 1, respectively. These choke slots therefore present a low series impedance so as to assist in the short-circuiting of the gaps.

The cavity resonator 50 is again equivalent to the cavity resonator as diagrammatically illustrated in Fig. 5, and the Equations 1-4 apply with equal force. In the case of this latter embodiment, the adjustable surface 56 enables the di-

mension *b* to be varied, while the plates 36 and 37 enables the dimension *l* to be varied.

If we now adjust *l* so as to match the wave pattern in the cavity resonator 50 to the position of the probes 64 and with a given value of *b*, the normal frequency of oscillation of the anode structure produces a value of λ which does not satisfy Equation 2, the value of *b* can be adjusted until said equation is satisfied. In this way the system can always be adjusted to a point of maximum efficiency since the anode structure can be permitted to oscillate at its normal unrestrained frequency.

If it is desired to tune the frequency of the device, such a tuning arrangement is also possible. For this purpose the value of *l* is fixed by the position of the plates 36 and 37 so as to produce the desired matching of the wave pattern with the positions of the probes 64. This likewise fixes the value of λg . If now the tuning surface 56 is varied so as to change the value of *b*, it will be noted that Equation 2 will require a corresponding change in the value of λ . This will require a corresponding change in the value of *f* pursuant to Equation 4. Under these conditions the cavity resonator 50 will reflect a sufficient amount of reactive impedance into the oscillating anode structure to pull the frequency thereof into accord with the frequency called for by the adjustment of the tuning surface 56. It will be noted, however, that such a tuning adjustment does not disturb the matching of the wave pattern within the cavity resonator to the position of the probes therein.

Of course it is to be understood that this invention is not limited to the particular details as described above as many equivalents will suggest themselves to those skilled in the art. It is accordingly desired that the appended claims be given a broad interpretation commensurate with the scope of the invention within the art.

What is claimed is:

1. A high frequency oscillator comprising an electron discharge tube having a plurality of oscillatory chambers therein, a cavity resonator adapted to be excited by said oscillatory chambers, a plurality of said oscillatory chambers being coupled directly to said cavity resonator at a plurality of points spaced along the length of said cavity resonator, said resonator incorporating adjustable means for shifting the position of the standing wave pattern established therein by said excitation, said resonator having a substantially rectangular cross-section with a dimension axially of said resonator greater than the width thereof, and means coupled to said resonator for adjusting said axial dimension for tuning said oscillator.

2. A high frequency oscillator comprising an electron discharge tube having a plurality of oscillatory chambers therein, a cavity resonator adapted to be excited by said oscillatory chambers, said resonator having a pair of closed ends defining a predetermined length of said resonator, a plurality of said oscillatory chambers being coupled directly to said cavity resonator at a plurality of points spaced along said length of cavity resonator, means in said resonator for adjusting the position of said ends relative to each other for adjusting said length, said resonator having a substantially rectangular cross-section with a dimension axially of said resonator greater than the width thereof, and means coupled to said resonator for adjusting said axial dimension for tuning said oscillator.

3. A high frequency oscillator comprising an electron discharge tube having a plurality of oscillatory chambers therein, a cavity resonator adapted to be excited by said oscillatory chambers, said resonator having a pair of closed ends defining a predetermined length l of said resonator, l being substantially equal to

$$\frac{n\lambda g}{2}$$

where n is a whole number and λg is the wave length of the radiations in said cavity resonator, a plurality of said oscillatory chambers being coupled directly to said cavity resonator at a plurality of points spaced along said length of cavity resonator, and separated from each other by a distance of

$$\frac{n_1\lambda g}{2}$$

where n_1 is a whole number, said resonator incorporating means for adjusting the position of said ends relative to each other for adjusting said length l , said resonator having a substantially rectangular cross-section with a dimension axially of said resonator greater than the width thereof, and means coupled to said resonator for adjusting said axial dimension for tuning said oscillator.

4. A high frequency oscillator comprising an electron-discharge device having a plurality of oscillatory chambers therein, and a cavity resonator adapted to be excited by said oscillatory chambers, a plurality of said oscillatory chambers being coupled directly to said cavity resonator, and said cavity resonator being provided with adjustable means for shifting the position of the pattern of the standing wave established therein by said excitation, whereby selected points along the length of said pattern may be selectively located with respect to the points of coupling between said oscillatory chambers and said cavity resonator.

5. A high frequency oscillator comprising an electron-discharge having a plurality of oscillatory chambers therein, and a cavity resonator adapted to be excited by said oscillatory chambers, a plurality of said oscillatory chambers being coupled directly to said cavity resonator at points spaced from each other by a distance

$$\frac{n_1\lambda g}{2}$$

where n_1 is a whole number and λg is the wave length of the oscillations in said cavity resonator, said cavity resonator being provided with adjustable means for altering the electrical length l thereof such that the position of the pattern of the standing wave established therein by said excitation results in selectively locating predetermined points on said pattern to the points of coupling between said oscillatory chamber and said cavity resonator, l being substantially equal to

$$\frac{n\lambda g}{2}$$

where n is a whole number.

6. In an electron-discharge device: a cathode

structure; an anode structure, spaced from said cathode structure, and provided with a plurality of oscillatory chambers therein; a cavity resonator surrounding said oscillatory chambers and being coupled to selected ones thereof, whereby said oscillatory chambers excite said cavity resonator; and means extending into said cavity resonator for shifting the position of the pattern of the standing wave established therein by said excitation, whereby predetermined points along the length of said pattern are matched to points of coupling between said oscillatory chambers and said cavity resonator.

7. In an electron-discharge device: a cathode structure; an anode structure, spaced from said cathode structure, and provided with a plurality of oscillatory chambers therein; a cavity resonator surrounding said oscillatory chambers and being coupled to selected ones thereof, whereby said oscillatory chambers excite said cavity resonator; and a pair of coating shorting plates movable in said cavity resonator for shifting the position of the pattern of the standing wave established therein by said excitation, whereby predetermined points along the length of said pattern are matched to points of coupling between said oscillatory chambers and said cavity resonator.

8. An electric discharge device comprising a substantially cylindrical envelope having an open end, a space resonant anode structure supported within said envelope, a structure for tuning said anode comprising a hollow metallic cylinder having an apertured end wall for the reception of a portion of said space resonant anode, and a flexible vacuum-tight connection between a second wall of said tuning structure and said envelope.

9. An electric discharge device comprising a substantially cylindrical envelope having an open end, a space resonant anode structure supported within said envelope, a structure for tuning said anode comprising a hollow metallic cylinder having an apertured end wall for the reception of a portion of said space resonant anode, and means connected with said tuning structure for producing relative movement between said anode structure and said tuning structure.
